UNITED STATES PATENT OFFICE.

CHARLES W. EPPERSON, OF SEATTLE, WASHINGTON, ASSIGNOR TO ALLEN M. CHESHIRE, OF SEATTLE, WASHINGTON.

WRENCH.

1,136,323.

Specification of Letters Patent. Patented Apr. 20, 1915.

Application filed June 8, 1914. Serial No. 843,871.

To all whom it may concern:

Be it known that I, CHARLES W. EPPERSON, a citizen of the United States of America, and a resident of the city of Seattle, in the county of King and State of Washington, have invented certain new and useful Improvements in Wrenches, of which the following is a specification.

My invention pertains to wrenches and has for its primary aim to provide a quick adjustable wrench which embodies simplified structural features thereby insuring of durability and ease of management.

The above and other objects I attain by the construction described in the following specification, succinctly defined in the appended claims and illustrated in the accompanying drawings wherein:

Figure 1 is a side elevation of my improved wrench. Fig. 2 is a top plan thereof, and Fig. 3 is a cross section taken on line 3—3 of Fig. 1 showing more clearly the mounting of the elements.

Referring by like characters of reference to corresponding parts throughout, 1 designates the fixed jaw having a hollow shank 2 on which slides the movable jaw 3, said shank being formed with a thickened, flat face 2' constituting a feather or key to receive the 30 similarly shaped key way of the sleeve support 3' of said movable jaw. The bore 4 of shank 2 extends partially the length thereof from the free end.

Shank 2 is formed with a spiral or inclined slot 5 extending over the curved face 2'' of the shank nearly the length of the key portion 2', while sleeve 3' of the movable jaw is provided with an inclined slot 6 arranged at a different pitch than slot 5 and 40 crossing the latter to have a portion thereof registering with a portion of the slot 5.

A manipulative handle 7 is provided with a rod 8 which is operable in bore 4 of shank 2 and carries a pin 9 fixed thereto for operation in the inclined slots 5 and 6. Pin 9 is preferably threaded into rod 8 and is provided with a shoe 10 for sliding in slot 6. This serves as a means for maintaining the

rod 8 and shank 2 together during the operation of the jaws.

In operation, the jaws 1 and 3 are placed about the object being gripped, and then the handle 7 is rotated in the proper direction to advance the pin 9 in the slots 5 and 6. This movement will close the jaws while the reverse will open the latter. It will be observed that just a slight turn of the handle is necessary to set quickly the jaws and that the full spacing or closing of the jaws will be accomplished in substantially a half turn of the handle.

Having thus described my invention, what I claim as new, and desire to secure by Letters Patent of the United States of America, is:—

1. A wrench comprising a fixed jaw having a hollow shank formed with an inclined slot, a movable jaw mounted on the shank of the fixed jaw and formed with a slot, a manipulative handle operable in the hollow shank, and a pin carried by the handle and operating in the slots of the jaws.

2. A wrench comprising a fixed jaw having a hollow shank formed with an inclined slot, a movable jaw mounted on the shank of the fixed jaw and formed with a slot, a manipulative handle operable in the hollow shank, a pin carried by the handle and operating in the slots of the jaws, and a shoe mounted on the pin and operable in the slot of the movable jaw.

3. A wrench comprising separable jaws, one slideable on the other and each provided with a cut-out arranged to cross the cut-out of the companion jaw, manipulative means rotatably mounted, and a pin carried by the manipulative means and operable in the cut-outs of the jaws for moving the latter toward and from one another.

Signed at Seattle, Washington, this 28th day of May, 1914.

CHARLES W. EPPERSON.
